UNITED STATES PATENT OFFICE

EDITH SPARKE, OF OAKLAND, CALIFORNIA

HAIRPIN

Application filed October 14, 1931. Serial No. 568,652.

The invention relates to hair pins and particularly to pins capable of being used in groups made up of two or more pins for cooperation with each other in retaining the hair in set position.

An object of the invention is to provide hair pins of the character described which may not only be set in the hair in cooperating relation with one another, but may be practically locked together in such cooperating relation so as to insure the retention of the pins as well as the hair in original set position as long as desired.

Another object of the invention is to provide hair pins with the above mentioned feature, which although when operatively set in the hair will not become accidentally displaced or released from the hair, may nevertheless be readily released from each other and removed from the hair when desired.

A further object is to provide hair pins having each of the aforementioned features, which may be operatively set in the hair as well as withdrawn therefrom by the person in whose hair the pins are set.

A still further object is to provide hair pins with such features, which may be concealed in the hair while operatively set therein.

The invention possesses other objects and features of advantage, some of which, with the foregoing, will be set forth in the following description of the preferred form of the invention which is illustrated in the drawing accompanying and forming part of the specification. It is to be understood, however, that variations in the showing made by the said drawings and description may be adopted within the scope of the invention as set forth in the claims.

Referring to said drawing:

Figure 1 is a perspective view of a hair pin designed in accordance with my invention.

Figure 2 is a perspective view of a pair of the pins in operative relation in the hair.

Figure 3 is a perspective view of a pin of somewhat simpler construction.

Figure 4 is a perspective view of a further modified form of the pin.

As illustrated in the drawing, the novel features of my invention are embodied in a hair pin 2 of the well known U-shaped form. In the preferred types of pin illustrated, the legs 3 of the pin are disposed in spaced generally parallel relation, but as shown in Figure 4 the legs may be bent toward each other so that normally they will be resiliently held in contact intermediate the inner and outer ends of the pin.

Each leg of the pins as illustrated in Figures 1 and 4 is formed adjacent its outer ends with a loop 6 whose greater length extends longitudinally of the leg.

In the preferred construction each loop extends from adjacent the outer extremity of the leg to a point adjacent the middle, so that a relatively large portion of each leg comprises the loop. In manufacturing the pin, the whole of the latter is preferably constructed of flat narrow ribbon metal stock of uniform cross section, the loop being conveniently formed by slitting the legs of the pin on the broader face and then spreading the slit portions apart to the desired degree and form. As will be clear from the drawing, the pin is so designed that the broader faces of the legs will be in opposed relation and consequently the loops will have the same transverse axis. The outer extremities of the legs are dull but have a fairly well defined point in order that the pin may readily enter the hair, in the preferred design the loop portions of the legs converging gracefully to the outer extremity so as to facilitate such entering operation. Likewise the inner loop portion converges smoothly into the inner leg portion so as to facilitate the withdrawal of the pins from the hair when desired, and preferably as shown in Figure 1 such leg portion 7 is cor-

rugated or otherwise bent or constructed to increase its retention effect.

In the use of the pins, as before explained, they are arranged to be used in multiple, that is in groups made up of two or more pins interlocked with one another. For instance, as illustrated in Figure 2, two pins are used together, one being inserted in the hair after the other. The pin first inserted is threaded in the hair in the usual manner so that a strand is held between the legs adjacent their connected ends, while other portions of the hair are entwined between and about the loop portions of the legs. With the first pin thus disposed the second one is then threaded through the hair at about right angles to the first pin and one or both of the legs of the second pin threaded through one or both of the loops of the first pin which the open face of the loop of one pin disposed along the longitudinal axis of the loops of the other pin. Then with the second pin thus positioned and engaged with the other, it is further extended and threaded through the hair and turned about its longitudinal axis when the loop portion thereof has passed through the loop of the other pin, whereby the open side aforesaid will extend transversely of the longitudinal axis of the first pin to thereby hold the pins in interlocking as well as cooperating relation. With the pins thus retained, as may be readily seen, the hair will be firmly held in set position and at the same time pins will be practically concealed. It is important to note that an effective interlocking of the pins may be effected by interengagement of but one leg of each of the pins in the group. If desired, additional pins may be threaded in the hair for cooperation and interlocking with the first two. When it becomes desirable to remove the pins they may be readily disengaged from each other and withdrawn from the hair by grasping the bent ends of the pins, separately or together, and then pulling them apart with the pins turned to allow the loop of one pin to pass freely through the other. It may be noted that where the pins are constructed of material appropriate to render the loop portions resilient, the withdrawal of the loops from engagement may be effected without the necessity of turning one with respect to the other.

In Figure 3, the pin is shown with the loop provided in only one of the legs, the other leg 12 being preferably connected and extended over the looped leg to facilitate the hair gripping effect.

I claim:

1. A hair pin, including a longitudinally extended leg having an opening therein adjacent one end thereof and extending to a point substantially midway between the ends thereof.
2. A hair pin comprising a leg extending longitudinally of the pin and having a wid-

ened portion adjacent a free end thereof and provided with an opening extended substantially to said end with one dimension of said opening being greater than the width of the leg at the widened portion and another dimension greater than the thickness of said leg portion whereby a similar leg portion of a second pin disposed at substantially right angles to said first named leg portion may be inserted through said opening.

3. A hair pin comprising substantially parallel legs integrally connected at one end and provided on at least one of the legs adjacent the free end thereof with a widened portion converging at one side gradually toward said free end and at the other side toward the closed end of the leg, said widened portion having an opening therein extending substantially to said free end with the dimension of said opening longitudinally of the leg being in excess of said widened leg portion and the dimension transversely of the leg greater than the thickness of said portion whereby a similar leg portion of a second pin disposed at substantially right angles to said first named leg portion may be inserted through said opening.

4. A hair pin comprising a pair of substantially parallel legs integrally connected at one end and having on each of the legs in opposed substantially parallel relation a widened portion with an opening therein having one dimension in excess of the width of said portion and another dimension greater than the thickness of said portion to thereby afford for the insertion of a widened portion a second similar pin through said opening when the pins are disposed at substantially right angles to each other.

5. A hair pin comprising a pair of substantially parallel legs integrally connected at one end and having on each of the legs in opposed substantially parallel relation a widened portion with an opening therein.

6. A hair pin comprising a pair of substantially parallel legs integrally connected at one end and having on each of the legs in opposed relation a widened portion with an opening therein extending substantially to said free end.

7. A hair pin comprising a pair of substantially parallel legs integrally connected at one end and having on each of the legs in opposed relation a widened portion, one of said portions having an opening therethrough, the other of said portions being corrugated and provided with undulations extending towards and away from said opening.

8. A hair pin comprising a pair of substantially parallel legs integrally connected at one end and having on each of the legs in opposed substantially parallel relation a widened portion with an opening therein,

each of said legs being provided between said opening and said end with a corrugated portion comprised of undulations extending toward and away from the other leg.

5 9. A hair pin comprising a pair of resilient legs integrally connected at one end and extended from said end in converging relation to lie in contactual engagement at their free ends, said legs being provided with
10 opposed widened portions adjacent said free ends with openings provided therein.

In testimony whereof I have hereunto set my hand at Oakland, California, this 3 day of October, 1931.

EDITH SPARKE.
